LEON BUEHLER, JR., AND CONRAD J. ROMBERG, OF WAYNESBORO, PENNSYLVANIA,
ASSIGNORS TO FRICK COMPANY, OF WAYNESBORO, PENNSYLVANIA, A CORPOR-
ATION OF PENNSYLVANIA

BLEEDER FOR AIR HEADERS

Application filed December 9, 1926. Serial No. 153,638.

Our said invention relates to bleeders for air headers and it is an object of the invention to provide means for keeping the temperature in an air header for supplying air used for agitating the water in the freezing cans of an ice making machine from being reduced sufficiently to freeze. In feeding air, for agitating, into the cans containing the raw water to be frozen there is usually a main header which supplies lateral or transversely disposed headers located between rows of cans or directly above the same and after the device has been in operation for some time the temperature is reduced to such an extent that the headers readily freeze and prevent the water from being agitated, thus affecting the efficient functioning of the device. In carrying out our invention we provide means for preventing the temperature from being reduced sufficient to cause the pipes to freeze by providing a bleeder passage or discharge opening at a point remote to the inlet end of the header so that a comparatively warm stream of air passes through the header at all times, all as will be hereinafter more particularly described and claimed.

Referring to the accompanying drawing, which is made a part hereof and on which similar reference characters indicate similar parts,

Figure 1 is a top plan view of a plurality of ice cans illustrating the application of our invention,

Figure 2, a detail,

Figure 3, a different arrangement of air header,

Figure 4, a section on line 4—4 of Figure 3, and

Figure 5, another form of air header.

In the drawing reference character 10 indicates a can grid or basket in which is mounted a plurality of ice cans 11 for containing raw water to be frozen. Along the can grid 10 is disposed an air lateral or header 12 having means at one end for connection with a main air header (not shown) and having tubes 13 arranged for supplying air to the cans, one of such tubes being supported by a bracket 14 over each can for supplying

air to that particular can. On the outer end of the air header or air lateral 12 is provided a bleeder 15 which may be of any desired form capable of being adjusted for varying the passage of air therethrough. As shown in Figure 2 the air bleeder comprises an inner disk 16 having an opening 17 therein and an outer disk 18 having an opening 19 therein. The upper disk is provided with a sleeve adapted to fit snugly on the end of the air header or pipe 12. With this construction by varying the size of the opening through the disks 16 and 18 the pressure of air within the air header or air lateral may be controlled, such bleeding action causing the temperature to be kept sufficiently high to prevent freezing of the pipes.

In lieu of air being fed into the header or lateral 12 at one end, as above described, and the bleeding operation occurring at the opposite end air may be fed into both ends of an air header or air lateral and the bleeding may take place about the center of the header, as shown in Figure 3. If desired a still different arrangement may be used which involves a feeding in of all the air at the center of the header or air lateral and bleeding the same at each end, as shown in Figure 5. If the structure of Figure 3 is used the bleeder, as shown in Figure 4, may consist of a sleeve mounted on the air lateral or header 10' or which has a perforation corresponding to the perforation in the sleeve and by rotating said sleeve the perforations may be brought into alinement.

The air laterals or headers are located under the tank lids and are therefore exposed to a cold temperature and the air within them is thereby chilled by both radiation and conduction. At the end of the laterals the velocity of the air becomes very low inasmuch as each air stream is feeding fewer and fewer cans as it approaches the end of the header. By allowing some air to blow off or escape from the end of the lateral at a point remote from the inlet the air which would become dead is kept in motion. In other words there is not a pocket of still or dead air from which a very small amount is fed to the can. When this air is allowed to remain motionless

or dead in the end of the lateral it rapidly becomes very cold consequently by our invention we can get air several degrees warmer at the last can if we allow some air to leak 5 out at the end of the lateral.

Our invention is quite simple, however, by controlling the temperature of the air within the header the device may be caused to more satisfactorily and efficiently perform 10 the function for which it is desired and a better freeze obtained.

It will be obvious to those skilled in the art that various changes may be made in our device without departing from the spirit of the 15 invention and therefore we do not limit ourselves to what is shown in the drawing and described in the specification but only as indicated in the appended claims.

Having thus fully described our said invention, what we claim as new and desire to secure by Letters Patent, is:

1. Ice making apparatus comprising a can grid, a plurality of cans in said grid, an air header mounted above and extending longitudinally of said grid, means for supplying air to each end of said header, an air bleed on and intermediate the ends of said header for allowing the slow escape of air from the header, and air laterals extending from 25 said header to said cans, said laterals being attached to the header between the air supplying means and the said air bleed, substantially as set forth.

2. Ice making apparatus comprising a support for ice cans, a plurality of cans in said support, an air header mounted above said support and extending across the tops of said cans, means for supplying air to each end of said header, a perforation in said header 30 intermediate its ends for allowing the slow escape of air from the header, a perforated sleeve about said header adapted to control the escape of air from the header, and air laterals from said header extending to said cans, said laterals being placed between the air supplying means and the said sleeve, substantially as set forth.

In witness whereof, we have hereunto set our hands at Waynesboro, Pennsylvania, this 50 first day of December, A. D. nineteen hundred and twenty-six.

LEON BUEHLER, JR.
C. J. ROMBERG.
